UNITED STATES PATENT OFFICE.

WALTER P. ALBERT, OF EAST ORANGE, NEW JERSEY, AND WARREN W. CARPENTER, OF BROOKLYN, NEW YORK, ASSIGNEES TO WESTERN ELECTRIC COMPANY, INCORPORATED, OF NEW YORK, N. Y., A CORPORATION OF NEW YORK.

TELEPHONE-EXCHANGE SYSTEM.

Application filed December 22, 1920. Serial No. 432,420.

To all whom it may concern:

Be it known that we, WALTER P. ALBERT and WARREN W. CARPENTER, citizens of the United States, residing at East Orange, in the county of Essex, State of New Jersey, and Brooklyn, in the county of Kings, State of New York, respectively, have invented certain new and useful Improvements in Telephone-Exchange Systems, of which the following is a full, clear, concise, and exact description.

This invention relates to telephone exchange systems and especially to those systems wherein machine switching apparatus is used for building up talking connections.

In the system disclosed herein connections to called subscribers' lines depend in part for their extension and supervision on operators at the central office. The operators receive the designations of the called lines and manipulate devices at their disposal, in accordance with such designations, which govern the selective movement of the automatic switches to set up the connections. The calling subscribers' lines are first attended by answering or A-operators. These operators may be either in the same office where the selective switches are located or at manual positions in distant offices according as the calling line is a local one or one belonging to an outlying office. Where the answering operator is situated in a distant office, her position is usually equipped with outgoing trunks leading to cordless positions at the central machine switching office. The operator in the originating office answers the calling subscriber and learns, for example, that the called line is one which must be reached through the central switching office. She thereupon communicates, over an order wire, the wanted number to the operator at the cordless position and requests the assignment of a trunk to be used for the connection.

The cordless operator in the central switching office assigns to the answering operator one of the idle trunks interconnecting their positions, and at the same time brings about the association of a register sending mechanism with this trunk. The cordless operator then sets up the called number on her keyboard which causes the positioning of the switch controlling registers. The registers of the sender there-

after serve to govern the automatic switches to selectively extend the connection through to the called line. The cordless operator having performed these duties ordinarily has no further interest in the call until it is time to release the automatic switches following conversation. She is, however, apprised of the manner in which the establishment of the connection progresses by means of indicating signals. The answering operator supervises the calling and called lines and initiates the release when conversation is over by taking down her cord circuit. This gives the cordless operator a disconnect signal and she, in turn, effects a release of the automatic switches.

It happens occasionally, during the establishment of the connection, that one of the automatic switches finds all trunks busy in the group over which it is hunting and goes to the overflow position. Further progress being defeated by such a condition, the cordless operator's attention should be called to the fact in order that she may restore the apparatus used in the partially completed connection.

The object of the present invention is, therefore, to provide, in a system of the foregoing character, means comprising a time measuring device rendered effective by the register to actuate a signal at the operator's position in the event that one of the selective switches finds all trunks busy.

A feature of the invention relates to means including a time measuring device rendered effective by the register sender when one of the selective switches finds all trunks busy for actuating a signal before the operator and means dependent upon the release of said switch for retiring the signal.

These and other features contemplated by this invention will become more readily understood from a consideration of the following description and the appended claims.

Referring to the drawing which forms a part of the application, Figs. 1 to 5 inclusive when arranged in the order illustrated in the diagram of Fig. 6 disclose a portion of a telephone system of the type to which the invention is applicable. At the left of the broken line in Fig. 1 there is shown the calling plug of an answering operator's cord circuit located in an originating office. To the left of the broken line there is also shown

the outgoing end of an interoffice trunk circuit which leads to a cordless operator's position in the central switching office. The remaining portion of this figure discloses the 5 trunk circuit at the cordless operator's position in the central switching office together with the necessary controlling and supervisory devices.

Fig. 2, at the left, shows a district or first 10 group selector switch in which the incoming trunk circuit terminates. To the right of Fig. 2 is shown a second group selector switch.

Fig. 3 illustrates a final selector or connector switch located in the same office and serving to complete the connections to called subscribers' lines.

Fig. 4 discloses a switching unit made up of two trunk finder switches which serve to 20 automatically associate an idle register sender with the particular trunk circuit at the cordless operator's position that has been taken for use in the extension of a connection. This figure further discloses an 25 allotter switch for assigning an idle register sender for use.

Fig. 5 shows a keyboard consisting of a plurality of rows of number keys located at the operator's position and one of a plurality of register sender units to which the 30 keyboard is common.

General description.

The automatic switches shown in Figs. 2 35 and 3 are of the two motion step-by-step type in which a primary stepping magnet operates in response to series of directive impulses to advance the brushes to select the desired group and then a secondary stepping magnet operates to step the brushes over the chosen group to select a set of terminals therein.

The trunk finders consist of single movement rotary step-by-step switches each made 45 up of a plurality of arcuate rows of terminals and cooperating brushes. A trunk finder unit consists of two of these rotary switches, one of which is designated TF^1 and the other is designated TF^2 . The purpose of utilizing two switches per unit is to 50 increase the number of trunk circuits at the operator's position that may be associated with the register sender. Half of the trunks, such as the trunk 107, 108 shown in 55 Fig. 1 at the operator's position are apportioned to the first trunk finder TF^1 and the remaining half of said trunks are apportioned to the second trunk finder TF^2 . When the operator assigns a particular 60 trunk for use by the distant operator, the first trunk finder switch commences to rotate and search for this particular trunk. If the assigned trunk is related to the second 65 trunk finder switch, the first trunk finder will continue to operate until it has made a

test of all the trunks which it serves. Thereafter, the second trunk finder switch TF^2 begins to operate and finds the desired trunk. In the drawing the several sets of terminals and brushes of each of the trunk finder switches of a given unit are enclosed within 70 the dotted rectangles. Within the lower rectangle are shown the stepping magnet 408 and the brushes and terminals belonging to the trunk finder TF^1 . The stepping magnet 409 and the several rows of terminals which comprise the second trunk finder TF^2 are shown within the area of the upper broken rectangle.

The operator's keyboard shown in Fig. 80 5 comprises four rows of ten keys each, designated as 500, 505, 510 and 515. By the use of these keys the operator may record any number in an office whose capacity is 10,000 lines. These keys are of the 85 locking type and any depressed key will remain in its actuated position until released by the energization of an electromagnet. The release magnets for the thousands, hundreds, tens and units keys are shown respectively at 528, 529, 530, 531 and 532. In addition to the ten number keys there is provided a common contact for each row. These contacts, which are identified by the characters 565, 566, 567 and 568, are closed 95 whenever one of the number keys in their corresponding rows is depressed.

The operator's keyboard briefly described above is common to a plurality of trunk finder and register sender units. One of 100 the register sender units at the operator's position is illustrated in detail in Fig. 5. The registers, of which there are four, one for each of the four digits in a subscriber's line number, comprise single motion step-by-step rotary switches. The thousands register 501 is provided with a stepping magnet 502, the hundreds register 506 with a stepping magnet 507, the tens register 511 with a stepping magnet 512 and the units register 110 516 with a stepping magnet 517, which magnets operate to step the brushes of their respective registers from position to position. The stepping magnets, the brushes and their coacting terminal banks and the other elements pertaining to each of the four registers are located within the spaces of the corresponding broken rectangles at the right of Fig. 5.

The sender control switch is likewise of 115 the step-by-step rotary single motion design. This switch consists of a stepping magnet 555 and a plurality of brushes and terminal rows. The several brushes of the sender control switch are, for convenience, 120 distributed throughout Fig. 5.

Each of the register sender units is, furthermore, equipped with a time measure switch, the function of which is to regulate 125 the advance of the sender control switch 130

from one position to another in such a manner that the automatic selective switches are given a sufficient time to complete a maximum trunk hunting operation. The time 5 measure switch generally designated by the letter "T," comprises a small rotary step-by-step device including a stepping magnet 545 and a plurality of brushes and terminal rows. The elements of this switch are 10 all confined within the area of the broken rectangle in the lower left-hand corner of Fig. 5.

In order that a trunk finder and register 15 sender unit may always be allotted for use when one is idle, and to avoid confusion in apportioning the same, an allotter switch AL is provided. The allotter switch likewise 20 consists of a small step-by-step device in which a stepping magnet 424 is designed to move the several switch contacts from one position to another. The several elements belonging to the allotter switch are located 25 within the area of the broken rectangle shown at the right of Fig. 4.

25 *Detailed operation.*

It is believed that a more thorough understanding of the invention may be had by giving a detailed description of the method 30 of operation of the system. To this end let it be assumed that a subscriber in the originating office illustrated by the disclosure at the left of the broken line in Fig. 1 has initiated a call. The answering or A-operator 35 at the originating office attends to the calling line in the usual manner and obtains the desired designation. On learning that the calling subscriber wishes to converse with a subscriber whose line belongs to the 40 machine switching office, she converses with the cordless operator in this latter office and informs her of the number of the called line. The order wire, which is used by the operators for communication with one another, is 45 not shown in the drawing, its purpose and function being well-known. The cordless operator selects an idle trunk circuit such as the trunk 107, 108 incoming to her position and communicates to the operator at 50 the originating office the identity of the trunk taken for use. The originating operator being given this information, inserts the calling plug 100 of her cord circuit in the jack 101 of the outgoing trunk, assigned 55 to her by the cordless operator. The insertion of the plug in the jack completes a circuit from battery through the winding of relay 102, sleeve of plug 100, sleeve of jack 101, left-hand winding of relay 106 to 60 ground at the contact and armature of the polarized relay 105. The right-hand winding of relay 106 is also included in series with the winding of relay 102. This latter winding of relay 106 is wound 65 with a high resistance so that the flow

of current therethrough is not great enough to permit the energization of relay 102. Since, however, the right-hand winding of relay 106 is shunted out at this time by the direct circuit to ground at the armature of relay 105, relay 102 becomes energized and closes a circuit for the supervisory lamp 103. Relay 106 also operates in series with relay 102 and closes the lower conductor of the trunk circuit 107, 70 108. The closure of the trunk establishes a circuit from battery, through the left-hand winding of relay 110, normal left-hand contact of relay 111, upper left-hand winding of repeating coil 109, conductor 75 107, upper right-hand winding of repeating coil 104, winding of the polarized relay 105, lower right-hand winding of repeating coil 104, contact and armature of relay 106, conductor 108, lower left-hand winding of repeating coil 109, right-hand normal contact of relay 111, right-hand winding of relay 110 to ground. Relay 110 80 operates, but the flow of current is in such a direction that the relay 105 at the originating office fails to energize. Consequently, the supervisory lamp 103 remains illuminated. Relay 110 completes a circuit from battery through the winding of relay 114 to ground at the contact and armature 85 of relay 110. Relay 114 establishes a circuit from battery, through the lamp 118, inner right-hand armature and back contact of relay 117, left-hand armature and back contact of relay 120, outermost right-hand armature and contact of relay 114 to ground. Lamp 118 illuminates in this circuit and serves as an indication to the cordless operator that the A-operator in the originating office has connected the calling 90 line to the assigned trunk.

At the time the cordless operator communicates the identity of the assigned trunk to the distant A-operator, she also depresses an assignment key 126, individual to said 100 trunk. The purpose of this key is to cause the operation of the allotted trunk finder to associate an idle register sender with the trunk to which said key is individual. A circuit is completed from battery, through the winding of relay 125, contacts of key 126, right-hand armature and contact of relay 122, back contact and right-hand armature of relay 124, closed contacts of key 127 to ground. Relay 125 operates and locks as follows, before the contacts of key 126 open when released by the operator: battery, through the winding and front contact and inner right-hand armature of relay 125 and thence to ground as traced at the left-hand contacts of key 127. Relay 125 establishes a circuit from ground, through its inner left-hand armature and contact, conductor 135, lower right-hand contact 425 (1) of the allotter switch, 125 130

brush 550 of the sender control switch, contact 569, conductor 442, winding of relay 406 to battery and ground. Relay 406 becomes energized and completes a circuit 5 from ground through its outer right-hand armature and front contact, conductor 433, terminal 570, brush 549, contact and armature and winding of stepping magnet 555 to battery and ground. The said magnet 10 555 energizes, interrupts its own circuit and deenergizes to advance the several brushes of the sender control switch onto their first position terminals.

It may be well to note at this time that 15 the sender control switch, the register switches, the time measure switch, the trunk finder switches and the allotter switch are all designed to advance the brushes from one terminal to another upon deenergization 20 of the stepping magnets.

With the sender control switch in its first position, the relay 406 is maintained energized, the circuit therefor being now closed through the brush 550 and terminal 571.

25 The stepping magnet 408 of the first trunk finder TF^1 commences to advance the brushes 410, 411, 412, etc., from position to position to search for the calling trunk circuit. The circuit for operating magnet 30 408 may be traced from battery, through the winding of said magnet, armature and contact thereof, conductor 443, through the connected terminals with which the brush 415 cooperates, intermediate left-hand armature and front contact of relay 406, terminal 35 444, brush 415 to ground. On the first operation of the stepping magnet 408, the several brushes of the trunk finder TF^1 advance to their first position terminals.

40 The operating circuit for the stepping magnet 408, thereafter leads over the conductor 443 and thence directly to ground through the connected terminals and brush 415. Since the calling trunk is not represented 45 in the terminals of the first trunk finder switch, the stepping magnet 408 will continue to operate until the brush 415 steps off the last one of the series of connected terminals and makes engagement with the 50 terminal 445. The circuit of magnet 408 being opened the switch comes to rest and a circuit is established as follows for operating the second trunk finder switch TF^2 :

55 battery through the winding and armature and contact of stepping magnet 409, front contact and innermost left-hand armature of relay 406, terminal 446, upon which the brush 422 of the second trunk finder switch is now standing; brush 422, terminal 445, 60 brush 415 to ground. Magnet 409 energizes, interrupts its own circuit and deenergizes to advance the brushes 417, 418, etc., to the terminals representing the first trunk in the group which is served by the switch TF^2 . 65 Hereafter, the operating circuit for the

stepping magnet 409 leads from battery, through the winding and armature and contact of said magnet, over the series of connected terminals which brush 422 is now engaging, terminal 445 and brush 415 to 70 ground. In parallel to this circuit, a circuit is established from battery, through the winding of relay 407, innermost left-hand armature and contact of relay 406, brush 422, terminal 445, brush 415 to ground. Relay 75 407 energizes for a purpose presently to be considered.

When the brushes of the second trunk finder reach the terminals identifying the assigned trunk circuit at the operator's position, a test circuit is closed from battery, through the winding of stepping magnet 409, front contact and left-hand armature of relay 407, winding of relay 402, contact and inner left-hand armature of relay 401, brush 80 411, terminal 447, brush 418, terminal 448, conductor 134, contact and outer left-hand armature of relay 125 to ground. The stepping magnet 409 energizes permanently in this circuit and the brushes are stopped in 85 engagement with the proper set of terminals. The relay 402 also becomes energized and establishes a circuit as above traced from battery, through the winding of magnet 409, front contact and left-hand armature of relay 407, thence through the winding and contact and left-hand armature of relay 402, conductor 435, brush 547 of the sender control switch, conductor 434, brush 410, brush 417, conductor 133, contact and outer 90 right-hand armature of relay 119, winding of relay 122, right-hand contacts of key 127 to ground. Stepping magnet 409, relay 402 and relay 122 are locked in this circuit. Relay 402 at its inner right-hand armature 95 closes an operating circuit for the relay 401. Relay 401 closes a holding circuit as follows for relay 407: battery, through the winding and inner right-hand armature and contact of relay 407, outer left-hand armature and contact of relay 401 to ground. Relay 401 also completes a circuit from battery through the winding of slow-to-release 100 relay 404, contact and right-hand armature of relay 403, outer left-hand armature and contact of relay 401 to ground. The function of the slow-to-release relay 404 will be 105 taken up hereinafter.

110 The relay 122 which also energizes in the holding circuit serves to extend the conductors 136 and 137, which constitute the impulse circuit, from the sender to the first group selector switch. Relay 122 at its right-hand armature and contact opens the holding circuit of relay 125. Relay 125 removes ground from conductor 135, whereby 115 relay 406 releases its armatures. Relay 122, furthermore, completes a circuit from ground through its outermost left-hand armature and contact, winding of relay 120 120 125 130

to the non-grounded pole of battery. Relay 120 becomes energized and at its left-hand armature and back contact opens the above traced circuit for lamp 118. Lamp 118, 5 however, remains illuminated in a circuit through the inner right-hand armature and back contact of relay 117, left-hand armature and front contact of relay 120, back contact and innermost left-hand armature 10 of relay 124 to ground.

Registration of called number.

It will be assumed that the number of the called subscriber's line 330, which is communicated by the originating operator over the order wire to the cordless operator in the machine switching office, is 9610. Accordingly, as soon as the cordless operator has assigned the trunk, she records the desired designation by depressing the proper keys in the thousands, hundreds, tens and units rows on the keyboard. The keys which she actuates are key 557 in the thousands row, key 558 in the hundreds row, key 559 in the tens row and key 560 in the units row. As soon as a key in each of the four rows has been actuated, the common row contacts are closed and circuits are established for the stepping magnets 502, 507, 25 512 and 517 of the registers. These circuits lead in parallel from battery through the windings and armatures and contacts of said magnets, conductor 449, lower left-hand contact 450 of the allotter switch, conductor 428, common contacts 568, 567, 566 and 565 to ground. The stepping magnets of the registers interrupt their own circuits and advance the brushes from terminal to terminal 30 in search of the depressed keys on the operator's keyboard. When the thousand register 501 finds the operated key 557, a circuit is closed from battery through the winding of magnet 502, winding of relay 503, brush 524 (position 1), brush 504, terminal 561, 35 key 557 to ground. When the register 506 finds the depressed key 558, a circuit is completed from battery through the winding of magnet 507, relay 508, brush 525 (1), brush 509, terminal 562, key 558 to ground. In a similar manner the circuits are completed 40 through the windings of magnets 512 and 517 and the corresponding relays 513 and 518 to ground, through the operated keys 559 and 560 respectively. When the registers reach positions corresponding to these 45 keys, the magnets are thereby permanently energized, and the brushes brought to rest. After the last register has found the depressed key, a circuit is closed from ground, 50 through the right-hand armatures and contacts of relays 518, 513, 508 and 503 in series, conductor 572, terminal 573, brush 548, contact and armature and winding of stepping magnet 555 to battery and ground. Magnet 555 55 interrupts its own circuit and advances

the sender control switch to its second position.

In position 2 of the sender control switch, the depressed keys on the operator's keyboard are released inasmuch as they are 70 no longer needed. The circuit for the release magnets 528, 529 etc., may be traced from battery, through the windings of these magnets in parallel, terminal 574, brush 551 to ground. With the keys released, the relays 503, 508, 513 and 518, become deenergized and close a series circuit from ground over their left-hand armatures and contacts, terminal 575, brush 548, contact and armature and winding of magnet 555 to battery 80 and ground. The stepping magnet 555 again energizes and advances the sender control switch into position 3. The register sender has thus received the record of the called subscriber's line and is now in condition to 85 transmit series of impulses in accordance with said record to operate the automatic switches to set up the necessary connection. The impulse circuit, which is completed over the left-hand armatures and front contacts 90 of relay 122, may be traced from battery, through the right-hand winding of relay 200 at the first group selector S1 back contact and inner left-hand armature of relay 207, conductor 129, middle left-hand armature and front contact of relay 122, conductor 136, brush 419, brush 412, back contact and left-hand armature of relay 400, contact and left-hand armature of relay 403, brush 413, brush 420, conductor 137, front 95 contact and innermost left-hand armature of relay 122, conductor 128, outer left-hand armature and back contact of relay 207, left-hand winding of relay 200 to ground. Relay 200 energizes and closes a circuit from 100 battery through the winding of slow-to-release relay 201, front contact and armature of relay 200, contact and outer right-hand armature of relay 207 to ground. It will also be noted that the relay 405 is included 105 in a circuit in parallel to the circuit leading through the contact and left-hand armature of relay 403. Relay 405, however, remains inert so long as its winding is shunted by the left-hand armature and contact of 110 relay 403.

Operation of first group selector.

When the sender control switch reaches 120 position 3, a circuit is established from battery, through the winding of relay 556, conductor 579, brush 544 and normal position terminal 576 of the time measure switch T, brush 536 (position 3) brush 520 to ground. Relay 556 becomes energized and closes a circuit from battery, through the winding of magnet 555, contact and left-hand armature of relay 556 to ground. At the same time, a circuit is closed from 125 ground through the front contact and in- 130

ner right-hand armature of relay 556, brush 539, brush 542, terminal 577, winding of stepping magnet 545 to battery and ground. Magnets 555 and 545 are energized preparatory to advancing their brushes to the next position when the operating circuits are opened. On the next closure of the constantly rotating interrupter 451, a circuit is completed from ground, through said interrupter, contact and outer right-hand armature of relay 401, conductor 436, winding of relay 552 to battery and ground. Relay 552 completes a circuit from ground, through its contact and inner left-hand armature, contact and outer right-hand armature of relay 556, left-hand armature and back contact of relay 554, winding of relay 553 to battery and ground. Relay 553 operates and completes a circuit from battery through its winding and contact and armature, winding of relay 554, conductor 579 and thence to ground at brush 520. Relay 554 does not energize since its winding is shunted by the direct circuit to ground at relay 552. As soon as the interrupter 451 opens, however, relay 554 becomes operated and locks in series with relay 553. The next closure of the interrupter 451 and the consequent energization of relay 552 results in the establishment of a circuit from ground, through the right-hand armature and contact of relay 554, outer left-hand armature and contact of relay 552, brush 537 (position 3), winding of stepping magnet 502 of the thousands register 501 to battery and ground. Magnet 502 attracts its armature and prepares to advance the brushes 504 and 520 to their next position terminals, when its circuit is severed. At the same time, a circuit is completed from ground, through the contact and inner left-hand armature of relay 552, contact and outer right-hand armature of relay 556, left-hand armature and front contact of relay 554, conductor 430, winding of the stepping relay 400 to battery and ground. Stepping relay 400 attracts its armatures, and opens the impulse circuit leading to the selector S1, thereby permitting the release of relay 200.

Relay 200 on retracting its armature closes a circuit from ground, through the outer right-hand armature and contact of relay 207, armature and back contact of relay 200, armature and front contact of relay 201—which remains energized during the transmission of impulses—winding of slow-to-release relay 202, winding of the primary stepping magnet 203 to battery and ground. Magnet 203 operates to advance the brushes 208, 209 and 210 into operative relation with the first group of terminals. Relay 202 likewise energizes and establishes a circuit from battery, through the winding of relay 206, lowermost springs

of the off normal contact 211, armature and front contact of relay 202, conductor 130, middle armature and contact of relay 120, left-hand contacts of key 127 to ground. It will be noted that the off normal contact 211 is closed the instant the brush shaft takes its first primary step. Relay 206 on energizing locks in a circuit from battery through its winding, lower springs of contact 211, armature and contact of magnet 205, contact and outer armature of relay 206 to ground at the contact and outer right-hand armature of relay 207. At the first primary step of the selector switch S1, a circuit is also closed from ground through the upper set of off normal springs 211, conductor 131, winding of relay 124 to battery and ground. Relay 124 at its right-hand armature and front contact provides a substitute ground connection from the left-hand contacts of key 127 to the conductor 130, so that this conductor will remain grounded when, later, the relay 120 releases its armatures.

Relay 124 at its innermost left-hand armature and back contact opens the circuit for lamp 118 and this lamp becomes extinguished. Relay 124 in addition completes a circuit from ground through the interrupter 123, middle left-hand armature and contact of said relay, front contact and innermost right-hand armature of relay 120, lamp 121 to battery and ground. Lamp 121 is flashed in this circuit to indicate to the operator that the establishment of the connection is proceeding.

The next opening of interrupter 451 causes the deenergization of relay 552 and the opening of the circuits of magnet 502 and relay 400. The magnet 502 advances its brushes to the next position and relay 400 closes the circuit for relay 200. Relay 200, in turn, opens the circuit through the windings of relay 202 and magnet 203 and recloses the circuit for relay 201. Magnet 203 deenergizes, but relay 202 being slow to release does not retract its armature. For each succeeding closure and opening of the interrupter 451, the relay 552 is operated to close and open the above traced circuits for the register stepping magnet 502 and the stepping relay 400. The register 501 advances from position to position while relay 400 causes the operation of relay 200, which in turn, causes the stepping magnet 203 to advance the brushes from one group of terminals to another. When all impulses have been sent, the brush 520 of the register 501 disengages the last grounded terminal and relay 556 becomes deenergized. Relay 556 opens the circuits of the stepping magnets 555 and 545. Magnet 555 releases the brushes of the sender control switch into position 4 and magnet 545 releases the brushes of the time measure switch to their

next position. Relays 553 and 554 are also released as soon as ground is removed from conductor 579. The time measure switch is driven through a complete cycle by means 5 of the interrupter 451, which continues to close and open circuit of relay 552. The stepping circuit for advancing the time measure switch may be traced from battery through the winding of magnet 545 over 10 the connected terminals cooperating with brush 542, brush 539, inner right-hand armature and back contact of relay 556, right-hand armature and contact of relay 552 to ground. The purpose of the time 15 measure switch, as stated hereinbefore, is to delay the advance of the sender control switch for a time somewhat greater than that required by the automatic switches to perform a maximum trunk hunting movement. Hence, while the time measure 20 switch T is stepping through a revolution, the first group selector S1 is performing its trunk hunting operation.

The stepping relay 400 remains permanently deenergized following the completion 25 of the first series of impulses and thereby maintains the energizing circuit for relay 200. After an interval, the slow-to-release relay 202 retracts its armature and a circuit 30 is closed from battery, through the inner armature and contact of relay 206, winding of the secondary stepping magnet 205, normal contacts of relay 202 to the grounded conductor 130. Stepping magnet 205 becomes 35 energized and advances the brushes 208, 209 and 210 on to the first set of terminals in the selected group. Magnet 205 at its armature and contact opens the holding circuit of relay 206, which thereupon 40 deenergizes and opens the operating circuit of magnet 205. Magnet 205 again becomes deenergized and closes the following circuit, provided the first trunk in the group is busy at this time: battery, through the winding 45 of relay 206, lower springs of off normal contact 211, armature and contact of magnet 205, back contact and inner right-hand armature of relay 207, brush 210 to ground on the test terminal 215 of the busy trunk. 50 In parallel to this circuit, a circuit also leads through the winding of relay 207 to the grounded conductor 130. Relay 207, however, is shunted out by the direct connection to ground at the busy test terminal 55 215 and cannot operate. Relay 206 operates to close the energizing circuit for the stepping magnet 205, which advances the brushes to the next set of terminals. This method of operation obtains until an idle 60 trunk is reached, the test terminal of which is identified by the absence of ground potential. Relay 206, therefore, fails to energize and the brushes of the switch are brought to rest. Relay 207 is now energized in series 65 with relay 206 to the grounded conductor 130, but the resistance of the relay 207 is such that enough current does not flow to also cause the operation of relay 206. The relay 207 at its front contact and inner right-hand armature extends the grounded conductor 130 through to test brush 210 and terminal 215 to render the selected trunk busy to other switches. Relay 207 at its left-hand armatures opens the circuit of relay 200 and extends the talking conductors 70 128, 129 through to the brushes 208 and 209. The impulse circuit for operating the second group selector S2 is established from battery through the right-hand winding of relay 220, back contact and inner left-hand armature of relay 216, terminal 214, brush 209, front contact and inner left-hand armature of relay 207, conductor 129 thence as above traced through the contact and armature of the stepping relay 400 and returning 75 by way of conductor 128, outer left-hand armature and front contact of relay 207, brush 208, terminal 213, outer left-hand armature and back contact of relay 216, left-hand winding of relay 220 to ground. 80 Relay 220 energizes and completes a circuit from battery through the winding of relay 217, contact and right-hand armature of relay 220, conductor 231 to the grounded test terminal 215. Relay 217 operates and locks 85 up in a circuit from battery through its winding and armature and contact and thence to the grounded conductor 231 independently of the right-hand armature and contact of relay 220. 90 95 100

Operation of second group selector.

When the time measure switch reaches the next to its last position, brush 542 disengages the last of the continuously connected terminals and steps on to terminal 578. A circuit is now completed from battery, through the winding of relay 403, conductor 439, terminal 580, brush 541, brush 540 and its fourth position terminal to 105 ground. Relay 403 operates to remove the shunt from around the winding of relay 405. The purpose of this is to permit the relay 405 to make a test of the impulse circuit to determine if the selector switch S1 has succeeded in finding an idle trunk. Since in the case assumed, an idle trunk was found, battery current is connected to the impulse circuit through the windings of relay 220 at the next switch S2 and relay 405 immediately operates when the shunt is removed at the left-hand armature and contact of relay 403. Relay 405 closes a circuit from battery through the winding of stepping magnet 545, conductor 438, contact and right-hand armature of relay 405, conductor 437, terminal 578, brush 542, brush 539 and thence to ground at the right-hand armature and contact of relay 552. The time measure switch T advances to its normal position. Relay 110 115 120 125 130

403 is thereupon released, the shunt closed and relay 405 becomes deenergized.

As soon as the time measure switch reaches its normal position, and since the 5 sender control switch is now in position 4, a circuit is immediately established from battery, through the winding of relay 556, conductor 579, brush 544, terminal 576, brush 536 (position 4), brush 521 of the 10 hundreds register 506 to ground. Relay 556 in the manner above described closes the energizing circuits of the stepping magnets 555 of the sender control switch and 545 of the time measure switch T. Upon 15 the next closure of the interrupter 451, relay 552 operates and closes the circuit for relay 553. Relay 553 energizes and prepares a circuit from battery, through its winding and contact and armature and the winding 20 of the relay 554 to the grounded conductor 579. Relay 554 energizes immediately that the interrupter opens and locks up in series with relay 553. At the next closure of the interrupter 451, a circuit is completed 25 from ground, through the right-hand armature and contact of relay 554, outer left-hand armature and contact of relay 552, brush 537 (4), winding of stepping magnet 507 to battery and ground. At the same 30 time the above traced circuit is closed from ground, through the contact and inner left-hand armature of relay 552, contact and outer right-hand armature of relay 556, left-hand armature and front contact of relay 35 554, conductor 430 and thence through the winding of the stepping relay 400 to battery and ground. Stepping magnet 507 is energized in order to advance the brushes 509 and 521 to the next position and relay 400 operates to open the impulse circuit to cause the release of relay 220 at the second 40 group selector switch S2. Relay 220 on de-energizing completes a circuit from ground through the outer right-hand armature and 45 contact of relay 216, left-hand armature and contact of relay 220, left-hand armature and front contact of relay 217, winding of slow-to-release relay 219, winding of the primary stepping magnet 221 to battery and ground. The stepping magnet 221 operates 50 and moves the brushes 225, 226 and 227 into operative relation with the first group of terminals. The relay 219 also becomes energized and completes a circuit from battery, 55 through the winding of relay 218, lower springs of the off normal contact 224—which operates on the first primary step of the switch—armature and front contact of relay 219 to the grounded conductor 231. Relay 218 attracts its armatures and closes a holding circuit for itself from battery, through the winding of said relay, lower springs of contact 224, armature and contact of the secondary stepping magnet 223, contact and outer armature of relay 218 to ground at the 60 65

contact and outer right-hand armature of relay 216.

Upon the next opening of the interrupter 451, relay 552 severs the energizing circuits of stepping magnet 507 and the stepping relay 400. Magnet 507 releases the brushes of the hundreds register to the next position and relay 400 closes the impulse circuit to cause the reenergization of relay 220. Relay 220 opens the circuit of relay 219 and 70 magnet 221. The magnet 221 becomes de-energized, but relay 219 being slow to release in character maintains its armature during the transmission of impulses. For each succeeding closure and opening of the constantly rotating interrupter 451, the stepping magnet 507 advances 75 the brushes of the hundreds register one position and the stepping relay 400 causes the primary stepping magnet 221 to move the 80 brushes of the second group selector successively to another group of terminals. When the last impulse of the series, represented by the depressed key 558, has been 85 transmitted to the switch, the brush 521 disengages the grounded terminals and relay 556 becomes deenergized. Relay 556 opens the holding circuits of the stepping magnets 555 and 545. Magnet 555 releases the 90 brushes of the sender control switch to their 95 fifth position terminals. The stepping magnet 545 advances the brushes of the time measure switch and this switch commences to make a complete rotation.

Following the completion of the impulse 100 series, relay 400 remains deenergized and relay 220 remains energized. After an interval has elapsed, the slow-to-release relay 219 becomes deenergized and a circuit is closed from battery, through the inner 105 armature and contact of relay 218, winding of the secondary stepping magnet 223, normal contacts of relay 219 to the grounded conductor 231. The stepping magnet 223 operates to move the brushes 225, 226 and 110 227 on to the terminals of the first trunk of the selected group. Magnet 223 opens the locking circuit of relay 218, which becomes deenergized and in turn opens the 115 energizing circuit of magnet 223. On the deenergization of magnet 223, a circuit is completed as follows, assuming the first 120 trunk in the group to be busy at this time and a ground potential to exist on the test terminal 230: battery, through the winding of relay 218, lower springs of the off normal contact 224, armature and contact of magnet 223, back contact and inner right-hand armature of relay 216, brush 227 to the 125 grounded test terminal 230. It will be noted that relay 216 is included in a circuit in parallel with the one just traced, but this relay cannot operate as it is shunted by direct circuits to ground at busy test terminals 230. Relay 218 operates and closes the 130

above traced circuit for magnet 223 which in turn operates to advance the brushes to the next set of terminals and also to open the circuit of relay 218. This method of operation continues until an idle trunk is found at which time, the shunt is removed from the winding of relay 216 and this relay operates in series with relay 218. The resistance of relay 216, however, is such as to prevent the operation of relay 218 and consequently the circuit of the secondary stepping magnet 223 is maintained open and the brushes of the switch are brought to rest on the terminals of the idle trunk. Relay 216 at its inner right-hand armature and contact extends the grounded third conductor through to the test terminal 230 to render the selected trunk busy to other second group selector switches. Relay 216 at its left-hand armatures opens the circuit of relay 220 and extends the talking conductors through to the connector switch C. The impulse circuit may now be traced from battery through the right-hand winding of relay 300, contact and outer left-hand armature of relay 304, conductor 326, terminal 229, brush 226 thence over the lower talking conductor, through the contact and armature of the stepping relay 400 at the sender, returning over the upper talking conductor to brush 225, terminal 228, conductor 325, normal contact at the outer left-hand armature of relay 305, left-hand winding of relay 300 to ground. Relay 300 becomes energized and closes a circuit from battery, through the winding of relay 301, contact and inner right-hand armature of relay 300, contact and inner right-hand armature of relay 304 to the grounded third conductor 327. Relay 301 locks in a circuit from battery, through its winding and contact and innermost right-hand armature, contact and innermost right-hand armature of relay 304 to conductor 327. Relay 300 also completes a circuit from battery through the winding of the slow-to-release relay 307, front contact and left-hand armature of relay 300, contact and outermost right-hand armature of relay 305, back contact and middle left-hand armature of relay 304 to ground.

Operation of connector switch.

Upon reaching the next to its last position, the time measure switch T stops temporarily and a circuit is closed from battery through the winding of relay 403, conductor 439, terminal 580, brush 541, brush 540 (position 5) to ground. Relay 403 removes the shunt from around the winding of relay 405 and this latter relay operates in series with the windings of relay 300 at the connector switch C. Relay 403 completes a circuit from battery, through the winding of the stepping magnet 545,

conductor 438, contact and right-hand armature of relay 405, conductor 437, terminal 578, brush 542, brush 539 and thence to ground at the right-hand armature and contact of relay 552, which operates on the next closure of interrupter 451. The stepping magnet 545, thereupon advances the time measure switch to its normal position and relay 403 becomes deenergized to reclose the shunt around the winding of relay 405.

Immediately that the time measure switch reaches its normal position, relay 556 is again energized in a circuit over conductor 579, brush 544, terminal 576, brush 536 (5), brush 522 of the tens register 511 to ground. Relay 566 closes the circuits hereinbefore traced for energizing the stepping magnets 555 and 545. On the first closure of the interrupter 451, relay 552 energizes and closes a circuit for relay 553, which in turn, completes a circuit for relay 554 as above described. As the interrupter opens, relay 554 energizes in series with relay 553 to the grounded conductor 579. The next time the interrupter 451 closes, a circuit is completed as hereinbefore traced for the stepping relay 400. A circuit is also closed from ground, through the right-hand armature and contact of relay 554, outer left-hand armature and contact of relay 552, brush 537 (5), winding of the stepping magnet 512 to battery and ground. Magnet 512 energizes preparatory to advancing the brushes of the tens register to their next position.

Relay 400 operates to open the impulse circuit, thereby causing the deenergization of relay 300 at the connector C. Relay 300 on deenergizing completes a circuit from ground, through the middle left-hand armature and back contact of relay 304, outermost right-hand armature and contact of relay 305, left-hand armature and back contact of relay 300, outer left-hand armature and contact of relay 301, contacts 313 and 315, winding of slow-to-release relay 302, winding of the stepping magnet 303 to battery and ground. The primary stepping magnet 303 actuates to advance the brushes 318, 319 and 320 of the connector switch into operative relation with the first group of terminals. Upon the first primary step of the switch contacts 313 and 315 disengage one another, but before this occurs, the contact 313 makes engagement with contact 314. Consequently, the original energizing circuit of the primary stepping magnet 303 is substituted by the circuit which leads as above traced, through the left-hand armatures and contacts of relays 300 and 301 thence by way of contacts 313 and 314, left-hand armature and front contact and winding of the slow-to-release relay, which is now energized, through the winding of

110
115
120
125
130

the primary stepping magnet 303 to battery and ground. The next time interrupter 451 opens relay 552 deenergizes and opens the circuits of the stepping magnet 512 and the 5 stepping relay 400. Magnet 512 advances the brushes of the tens register to their next position terminals and relay 400 closes the impulse circuit to permit the energization of relay 300. Relay 300 opens the circuit 10 through the slow-to-release relay 302 and stepping magnet 303. The stepping magnet becomes deenergized, but relay 302 retains its armatures during the transmission of impulses. For each succeeding impulse sent 15 out by the register sender, the stepping magnet 512 operates to advance the brushes one step, while relay 300 operates to cause the primary movement of the connector switch. Following the last impulse of the series, the 20 brush 522 of register 511 disengages the last grounded terminal and opens the circuit of relay 556. Relay 556, in turn, opens the circuits of stepping magnets 555 and 545, whereupon the sender control switch moves 25 out of position 5 and into position 6 and the time measure switch commences to make a complete revolution of its brushes. After the lapse of the necessary interval, 30 during which relay 300 is holding its armatures attracted by reason of the fact that the stepping relay 400 at the sender is permanently deenergized, the slow-to-release relay 302 retracts its armatures. Relay 307 being slow to release remains energized 35 during the vibration of the armatures of relay 300.

When the time measure switch, which commences to rotate upon the deenergization of relay 556, reaches its sixth position, 40 brush 543 makes engagement with the first one of the connected terminals 581 and a circuit is established as follows: ground, through brush 543, terminal 582, brush 548, contact and armature and winding of stepping magnet 555 to battery and ground. The magnet 555 operates in this circuit to 45 advance the sender control switch from position 6 into position 7. Upon reaching the next to the last position, the time measure 50 switch completes a circuit from battery, through the winding of magnet 545, the seventh position terminal coacting with brush 546, brush 546, terminal 578, brush 542, brush 539 and thence to ground at the right-hand 55 armature and contact of relay 552. Magnet 445 energizes and upon the opening of interrupter 451 deenergizes to advance the time measure switch into its normal position. It will be observed that the brush 60 540 does not close the conductor 439 to ground in the sixth and seventh positions of the sender control switch and consequently, relay 403 remains deenergized.

With the sender control switch in 65 position 7 and the time measure switch at nor-

mal, a circuit is closed from battery, through the winding of relay 556, conductor 579, brush 544, terminal 576, brush 536 (7), brush 523 of the units register 516 to ground. Relay 556 operates to close the circuits for stepping magnets 555 and 545. When the interrupter 451 closes, relay 552 becomes energized and establishes a circuit for the relay 553, which in turn, closes a series circuit for itself and relay 554 to the 70 grounded conductor 579. On the next opening of the interrupter, relay 554 locks in series with relay 553. Following this, the closure of interrupter 451 causes the operation of relay 552 and the above traced circuit is established for the stepping relay 400. Also, a circuit is closed from ground, through the right-hand armature and contact of relay 554, outer left-hand armature and contact of relay 552, brush 537 (7), 75 winding of stepping magnet 517 to battery and ground. Magnet 517 energizes preparatory to advancing the brushes of the units register to their next position terminals and the relay 400 attracts its armature to open the impulse circuit, thereby causing the deenergization of relay 300 at the connector switch.

Relay 300 upon deenergizing establishes a circuit from ground, through the middle 80 left-hand armature and back contact of relay 304, outer right-hand armature and contact of relay 305, left-hand armature and back contact of relay 300, outer left-hand armature and contact of relay 301, contacts 313 and 314, left-hand armature and back contact of relay 302, winding of slow-to-release relay 324, winding of the secondary stepping magnet 309 to battery and ground. Magnet 309 operates to advance the brushes 85 318, 319 and 320 into engagement with the first set of line terminals in the selected group. Relay 324 also energizes in series with the stepping magnet and retains its armatures during the transmission of the units impulses. In the manner now well understood, the stepping relay 400 energizes and deenergizes to send impulses over the impulse circuit and the units register stepping magnet 517 is operated to restore the 90 units register 516 to its normal position. When the last impulse of the units series has been sent, which means that the brushes of the connector switch have been driven to the terminals of the called subscriber's line 330, brush 523 of the register disengages the grounded terminals and opens the circuit of relay 556. Relay 556, in turn, opens the circuits of stepping magnets 555 and 545. Stepping magnet 555 releases the 95 brushes of the sender control switch out of position 7 and into position 8 and magnet 545 commences to operate to drive the time measure switch through a complete cycle. Before continuing to describe the manner 100

in which the called subscriber's line is tested and ringing current applied thereto at the connector switch, the release of the register sender will be first taken up and also the effect of its release upon the circuits at the first group selector.

Release of register sender.

When the time measure switch reaches position 6, its brush 543 encounters the first connected terminal 581 and a circuit is closed as follows: ground, through the brush 543, brush 548 and its eighth position terminal, contact and armature and winding of stepping magnet 555 to battery and ground. The stepping magnet 555 operates to advance the sender control switch into position 9. In this position the circuit just traced is reclosed by brush 548 and magnet 555 again energizes and deenergizes to move the sender control switch out of position 9 and into position 10. The passage of the sender control switch through positions 8 and 9 takes place while the brush 543 of the time measure switch is moving over the connected terminals 581. As the sender control switch leaves position 9, its brush 547 opens the circuit hereinbefore traced for magnet 409, relay 402 and relay 122. Relay 402 at its inner right-hand armature and contact opens the circuit of relay 401. Relay 401 becomes deenergized and disconnects the interrupter 451 from conductor 436. Relay 401 also completes a circuit from battery, through the winding and armature and contact of magnet 555, brush 549, conductor 431, contact and inner right-hand armature of relay 401 to ground at the back contact and outer right-hand armature of relay 406. Magnet 555 interrupts its own circuit and advances the sender control switch into its normal position. Relay 401 at its outer left-hand armature opens the holding circuit of relay 407 and this latter relay retracts its armatures. The magnet 409 which also deenergizes at this time, advances the brushes of the trunk finder TF^2 to their next terminals. The trunk finder TF^2 is now restored to its normal position by means of a circuit from battery through the winding and armature and contact of magnet 409, through the connected terminals with which brush 422 cooperates, terminal 445 and brush 415 to ground. When the trunk finder TF^2 reaches normal, brush 422 engages terminal 446 and a circuit is completed from battery, through the winding of relay 407, terminal 446, brush 422, terminal 445 and brush 415 to ground. Relay 407 operates and closes a circuit from battery, through the winding and armature and contact of magnet 408, contact and outer right-hand armature of relay 407, contact and outermost left-hand armature of relay 406, terminal 452, brush 416, brush 423 and its

normal position terminal to ground. Stepping magnet 408 operates in this circuit and advances the brushes of the trunk finder TF^2 to their normal positions. The trunk finder switches now being restored, both magnets 409 and 408 remain inactive and relay 407 is released.

Relay 122 on deenergizing at the time the sender control switch moves into position 10, disconnects the talking conductors 128 and 129 from the impulse conductors 136 and 137 and extends said talking conductors through to the right-hand windings of the repeating coil 109 in the trunk circuit. Relay 122 at its outer left-hand armature opens the circuit of relay 120. Relay 120 at its innermost right-hand armature opens the circuit for flashing the lamp 121. The termination of the flashing of lamp 121 indicates to the operator that all selections have been completed and the sender disassociated from the trunk circuit. Relay 120 also completes a circuit from battery through the winding of slow-to-release relay 116, back contact and inner left-hand armature of relay 117, contact and outer right-hand armature of relay 120 to ground at the contact and outermost left-hand armature of relay 124. Relay 116 becomes energized and closes a circuit from battery, through the winding of relay 113, armature and contact of relay 116 to ground at the front contact and left-hand armature of relay 114. The closure of this latter circuit depends upon the fact that relay 114 is still energized, which will be the case provided the operator in the originating office has not in the meantime withdrawn the plug 100 from the jack 101. Relay 113 operates and completes a circuit from ground, through its right-hand armature and contact, winding of relay 117 to battery and ground. Relay 117 operates and locks in a circuit battery, through its winding and front contact and inner left-hand armature, contact and outermost right-hand armature of relay 120 to ground at the contact and outermost left-hand armature of relay 124. Relay 117 opens the circuit of relay 116, which after an interval retracts its armature and permits the deenergization of relay 113. With relay 117 operated, a circuit is now closed from battery, through the lamp 121, innermost right-hand armature and back contact of relay 120, outer right-hand armature and contact of relay 117, middle right-hand armature and front contact of relay 114 to ground. The lamp 121 is steadily illuminated, which advises the operator that the originating operator is still waiting for the connection to be completed.

It will be assumed that the called line 330 is idle at the time the connector switch C sets its brushes on the terminals thereof. This being true, a circuit is closed as follows, as soon as the slow-to-release relay 324

retracts its armatures following the last units impulse: battery, through the winding of cut-off relay 312, terminal 321, brush 320, right-hand armature and back contact of relay 324, contact and innermost left-hand armature of relay 311, right-hand winding of relay 304, front contact and middle right-hand armature of relay 301, back contact and middle left-hand armature of relay 304 to ground. Relay 304 becomes energized in this circuit. The contacts and armatures of this relay are so arranged that the inner left-hand armature makes its front contact slightly in advance of the opening of the middle left-hand armature and its back contact. Therefore, before the original energizing circuit of relay 304 can be opened at the middle left-hand armature of said relay, the following substitute circuit is closed to hold said relay operated: battery, through the left-hand winding and front contact and inner left-hand armature of relay 304 to the grounded conductor 327. Relay 304 opens the circuit of relay 300 and also the locking circuit hereinbefore traced for relay 301. Relay 300 on deenergizing opens the circuit of relay 307, which after an interval retracts its armatures.

30 The ringing circuit is now established for applying ringing current to the called subscriber's line and may be traced from the ringing source 328, interrupter 329, left-hand winding of relay 305, back contact and inner left-hand armature of relay 305, contact and outermost right-hand armature of relay 304, outer right-hand armature and contact of relay 311, brush 319, thence over the loop of the called line 330, brush 318, back contact and inner right-hand armature of relay 311, middle right-hand armature and contact of relay 304 to ground at the outer left-hand armature and back contact of relay 305. The relay being marginal does not operate in series with the magnet of the ringer at the called substation. When the called subscriber responds by removing the receiver from the switchhook, the resistance of the ringer magnet is removed and sufficient current flows through the left-hand winding of relay 305 to cause the energization thereof. The armatures and contacts of relay 305 are so arranged that the inner right hand armature and contact are closed slightly in advance of the opening of the left-hand armatures and their back contacts. Relay 305 therefore immediately locks up in a circuit from battery, through its right-hand winding and contact and innermost right-hand armature, normal contacts of relay 307, conductor 325, thence over the upper talking conductor through the switches S² and S¹ to conductor 128, innermost left-hand armature and back contact of relay 122, back contact and left-hand armature

of relay 113, upper right-hand winding of repeating coil 109 to ground. Relay 305 at its left-hand armatures opens the ringing circuit and completes the talking conductors 325 and 326 through to the called subscriber's line. A complete circuit is now established from the called subscriber's line to the right-hand windings of repeating coil 109, battery current being supplied through the winding of relay 112. Relay 306 which is included in this circuit becomes energized and closes a circuit for slow-to-release relay 307. Relay 307 at its right-hand armature make-before-break contact opens the above traced holding circuit for relay 305 and closes a substitute circuit as follows: battery, through the right-hand winding and contact and innermost right-hand armature of relay 305, front contact and right-hand armature of relay 307 to the grounded third conductor 327. This act removes the right-hand winding of relay 305 from the tip side of the line and connects it to the third conductor.

Relay 112 which also energizes in series with the called subscriber's line completes a circuit from battery through the winding of relay 111, contact and left-hand armature of relay 112 to ground at the contact and armature of relay 110. Relay 111 operates and by means of its make-before-break contacts reverses the connections of the winding of relay 110 to the trunk conductors 107 and 108. This reversal causes current to flow in the opposite direction through the winding of the polarized relay 105 at the outgoing end of the trunk in the originating office. Relay 105 now operates and removing the shunt from the right-hand high resistance winding of relay 106, causes the relay 102 to become deenergized. Relay 102 effaces the lamp 103 which indicates to the originating operator that the called subscriber has answered.

After conversation has ceased and the calling subscriber has hung up his receiver, the operator in the originating office initiates release by withdrawing the plug 100 from the jack 101. The removal of the plug from the jack opens the circuit of relay 110 at the cordless operator's position. Relay 110, in turn, opens the circuit of relay 114 and a circuit is thereupon closed from battery, through the lamp 118, inner right-hand armature and front contact of relay 117, innermost right-hand armature and contact of relay 114, interrupter 115 to ground. Relay 114 also closes a circuit from battery through lamp 121, inner right-hand armature and back contact of relay 120, outer right-hand armature and contact of relay 117, middle right-hand armature and contact of relay 114, interrupter 115 to ground. The flashing of lamps 118 and 121 in these circuits informs the cordless operator that the connec-

tion should be taken down. To accomplish this, she manipulates her disconnect key 127. Key 127 on being depressed opens the ground connection to conductor 130. The removal of ground from conductor 130 permits the deenergization of relays 207, 216 and 305. Relay 207 completes a circuit from battery, through the winding of release magnet 204, middle springs of the off normal contact 211, back contact and armature of relay 201, back contact and armature of relay 200, contact and outer right-hand armature of relay 207 to ground. The release magnet 204 operates to restore the brushes of the selector switch S1 to their normal position, at which time the off normal contact 211 opens and magnet 204 becomes deenergized. In a similar manner, a circuit is closed from battery, through the winding of release magnet 222, upper springs of the off normal contact 224, back contact and left-hand armature of relay 217, contact and left-hand armature of relay 220 to ground at the contact and outer right-hand armature of relay 216. It will be noted that relay 217 became deenergized at the time ground potential was removed from conductor 130 and conductor 231. The release magnet 222 operates to restore the brush shaft of the selector switch S² to its normal position. When ground is removed from the third conductor 327 at the connector switch, relay 304 also releases its armatures. A circuit is now closed from battery, through the winding of release magnet 308, contacts 317 and 316, back contact and middle right-hand armature of relay 301, back contact and middle left-hand armature of relay 304 to ground. Magnet 308 energizes and causes the brush shaft of the connector switch C to restore to its normal position. When the normal position is reached, the off normal contacts 316 and 317 are opened and magnet 308 deenergizes. The entire connection has thus been restored to its normal position and the apparatus involved may again be taken for use in connection with further calls.

50   *Allotment of register senders.*

A consideration will now be given to the method of allotting the register sender units for use in controlling the selective switches. According to the disclosure in this case, the 55 register sender shown in detail is allotted for use when the allotter switch AL is standing in position 1. As will presently be seen, the next register sender mechanism (not shown) is assigned for use in position 3 of the allotter switch. After the allotted register sender has been associated with the cord circuit in the manner described and the registration set up on the numerical registers, the allotter switch AL is advanced for the purpose of assigning the next idle sender. This 65 advance occurs when the sender control switch reaches position 4. At that time, a circuit is completed from battery through the winding and armature and contact of the allotter, stepping magnet 424, upper 70 right-hand contact 427 (1+2), to ground through the fourth position terminal and brush 551 of the sender control switch. The allotter magnet 424 operates to advance the contacts of the allotter switch into position 3. 75 If the next register sender happens to be busy at this time, the allotter switch continues to move into position 5 by means of a circuit similar to the one traced for driving said switch into position 3. Should the next 80 register sender be idle, the allotter switch stops in position 5. The next time an assignment key 126 is depressed by the cordless operator, the grounded start conductor 135 is extended by way of the upper right-hand contact 425 (5), and thence through the winding of a relay, corresponding to relay 406, individual to the allotted register sender unit.

Should all the register senders be engaged 90 simultaneously, a circuit is completed from battery through the winding of relay 534, conductor 432, contact 453, outer right-hand armature and contact of relay 402, thence through the outer right-hand armature and 95 front contacts of each of the relays corresponding to relay 402 individual to the other register senders to ground. Relay 534 becomes energized and closes a circuit from battery, through the windings of the key release magnets 528, 529, etc., to ground at the front contact and armature of said relay. The release magnets are operated to insure 100 that none of the keys on the operator's keyboard can be locked in their actuated position until one of the register senders become available for use. Since all of the register senders are busy, the allotter switch 424 continues to advance from one allotting position to another by means of circuits similar 105 to the one described in detail, until it reaches its position 13. In this position, a circuit is completed from battery, through the winding and armature and contact of magnet 424 to ground on the lower left-hand contact 427 (13+17). The stepping magnet 424, therefore, continues to operate until the switch reaches position 18, where it comes to rest. When one of the register senders becomes idle, the series circuit 110 through the armatures and contacts of relays 402 is opened and relay 534 becomes deenergized. Relay 524 at its armature and back contact closes a circuit including contact 426 (18) to drive the allotter switch 115 into its first allotting position. The idle register sender is immediately found by the allotter and assigned.

125

Called line busy.

It will be next considered that the called subscriber's line 330 is busy at the time the connector switch advances its brushes into engagement with the terminals thereof. If, for example, the line 330 is busy as a called line, a ground potential will exist on the test terminal 321 by reason of the following circuit: ground, through the middle left-hand armature and front contact of relay 304, innermost left-hand armature and contact of relay 311, back contact and right-hand armature of relay 324, test brush 320 to the test terminal 321. Consequently, as soon as the brush 320 encounters terminal 321 and before relay 324 has time to release, a circuit is completed from battery, through the winding of relay 311, front contact and right-hand armature of relay 324 to the grounded test terminal 321. Relay 311 attracts its armatures and locks up over the following circuit, as soon as the slow-to-release relay 324 becomes deenergized: battery, through the winding of relay 311, make-before-break contact at the right-hand armature of relay 324, back contact and right-hand armature of relay 310, contact and outermost left-hand armature of relay 311 to the grounded conductor 327. Relay 311 at its right-hand armatures opens the talking conductors to prevent the application of ringing current to the called subscriber's line. Upon the first closure of the interrupter 323 following the actuation of relay 311, a circuit is established from ground, through the left-hand winding of the tone coil 322, interrupter 323, inner left-hand armature and contact of relay 324, contact and middle left-hand armature of relay 311, outermost right-hand armature and front contact of relay 301, left-hand winding of relay 304 to battery and ground. Relay 304 becomes energized and locks up in a circuit through its left-hand winding and contact and innermost left-hand armature to ground, over the conductor 327. Relay 304 opens the circuit of relays 300 and 301. After relay 301 becomes deenergized, a circuit is established for each closure of the interrupter 323 and may be traced from ground, through the left-hand winding of tone coil 322, interrupter 323, inner left-hand armature and contact of relay 324, contact and middle left-hand armature of relay 311, outermost right-hand armature and back contact of relay 301, right-hand winding of relay 300 to battery and ground. The interrupted current flowing in this circuit induces a current in the left-hand winding of relay 300 which is transmitted over the upper talking conductor to the windings of the repeating coil 109 and thence to the windings of repeating coil 104 and thence to

the calling subscriber's receiver. This 65 characteristic tone in the receiver informs the calling subscriber that the called line is busy at this time. He thereupon hangs up his receiver and the originating operator initiates the release. The cordless operator, 70 in turn, effects a disconnection of the automatic switches in the manner already discussed.

All trunks busy.

Coming now to that phase of the system which relates more particularly to the invention, the method of producing an overflow signal at the cordless operator's position to notify her that some one of the automatic switches has found all trunks busy will be taken up in detail. Consider first that the first group selector switch S1 in performing its trunk hunting operation fails to find an idle trunk leading to the proper group of selector switches S2. As was explained hereinbefore, the sender control switch passes out of position 3 and into position 4 immediately following the completion of the transmission of the series of impulses for causing the primary operation of the selector switch S1. With the sender control switch in position 4, the relay 403, as above described, is energized in a circuit from battery through the winding of said relay, conductor 439, terminal 580, brush 541, as soon as time measure switch T reaches the next to its last position, brush 540 of the sender control switch in position 4 to ground. Relay 403 attracts its armatures and opens the normally closed shunt circuit around the winding of relay 405. This includes the winding of relay 405 directly in series with the impulse circuit leading to the brushes 208 and 209 of the first group selector switch S1. In the normal operation, namely when the selector switch finds an idle trunk, battery current is connected through the windings of a relay such as relay 220 to the brushes 208 and 209. Consequently, in this case, relay 405 becomes energized as soon as relay 403 operates, but since all trunks in the group are now busy, the brushes 208 and 209 of the first group selector have gone to the overflow position and battery current is not connected to the impulse circuit. Under these circumstances, relay 405 remains inert following the operation of relay 403 and the above traced circuit for driving the time measure switch into its normal position is held open. After the lapse of the necessary interval following the operation of relay 403, the slow-to-release relay 404 becomes deenergized due to the fact that its circuit is severed at the contact and right-hand armature of relay 403. Relay 404 completes a circuit from ground, through its armature
